UNITED STATES PATENT OFFICE.

DAVID F. CURTIN. OF CHICAGO, ILLINOIS.

DISK-TOOL.

1,188,047.

Specification of Letters Patent. Patented June 20, 1916.

Application filed August 11, 1914, Serial No. 856,205. Renewed November 11, 1915. Serial No. 80,995.

To all whom it may concern:

Be it known that I, DAVID F. CURTIN, a citizen of the United States, and a resident of Chicago, in the county of Cook and State of Illinois, have invented a new and useful Improvement in Disk-Tools, of which the following is a specification.

My invention is an improvement in disk tools, and has for its object to provide a tool of the character specified for creasing and folding circular blanks or disks of paper into the dishes forming the subject-matter of my copending application, Serial No. 842,672, filed June 3, 1914.

15 In the drawings: Figure 1 is a top plan view of the improved tool showing the first step in the operation of creasing and folding the blank, Fig. 2 is a similar view showing the second step, Fig. 3 is an enlarged top 20 plan view showing the third step, Fig. 4 is a section on the line 4—4 of Fig. 3, Fig. 5 is a top plan view of a portion of the tool, and Fig. 6 is an edge view of Fig. 5.

The present embodiment of the invention comprises a pair of gripping jaws 1 and 1^a, of isosceles triangular form. The sides of the plates 1 and 1^a are at an angle of 45° with respect to each other, and they are connected at their base.

25 The plates or jaws 1 and 1^a are in the form of plates arranged in spaced relation and approximately parallel, and they are formed from a single sheet cut to diamond shape. The diamond figure is then slotted transversely at its center, and the plate is folded upon the slot. Thus the jaws 1 and 1^a are 30 connected by integral portions 2 at each end of the base, and the connections are resilient, so that the plates may be moved toward and 35 from each other, but will normally hold the position shown in Fig. 6.

A handle comprising a grip 3 of wood or other suitable material, is connected with the jaws, by means of a shank 4. The plate 45 4 is soldered or brazed to the outer face of one of the plates or jaws, the plate 1 in the present instance, and a portion thereof extends beyond the base of the said plate and is reduced as indicated at 5, and is inserted 50 in an opening in the grip or handle 3.

A ferrule 6 of metal is preferably arranged around the end of the grip or handle 3, adjacent to the gripping jaws for holding the parts in proper position. The altitude of 55 the jaws is dependent upon the size of the dish to be formed.

The dishes referred to are formed from a circular blank or disk 7, and to crease and fold a blank into shape, the blank is engaged by the gripping jaws as shown in Fig. 1, and the jaws are of such length that when the periphery of the surface of the blank engages the integral connections 2, the points of the plates or jaws will be at the center of the blank. With the jaws in this position either the blank or the gripping jaws is turned to fold that portion of the blank held between the jaws over upon the body of the blank, and the fold between that portion of the blank between the jaws and that portion beneath both jaws may be creased by pressing the plate or jaws together. This second step is shown in Fig. 2. The body of the blank is now opened out, that is, the blank is bent or folded over upon the uppermost plate in such manner that that portion which is held between the jaws is creased at each side edge, the folds being opposite. The tool is now withdrawn, and the blank is folded and creased in such manner that when the two folds are folded upon each other as indicated in Fig. 4, a conical dish will be formed. A conical dish is thus formed, having a flap and the dishes are intended to be held in the holders, forming the subject-matter of my copending applications Serial No. 805,035, filed Dec. 6, 1913, and Serial No. 842,671, filed June 3, 1914. It will be evident from the description above that the blanks may be folded rapidly by a single motion of the tool. With the blank gripped as shown in Fig. 1, it is only necessary to turn the tool once over and both folds and creases are made.

With the parts in the position of Fig. 1, as the tool is turned, the fingers of the left hand engage that portion which is beneath the tool in Fig. 2, while the thumb engages that portion which is above the tool in Fig. 3. The folding motion is completed by merely reversing the tool, and it may be withdrawn as soon as the fold is made. By arranging the connection between the jaws at the ends of the base and leaving that portion of the jaws disconnected between the said connections, the periphery of the blank may pass through this open space as shown in Fig. 3.

I claim:—

1. A tool of the character specified, comprising a pair of gripping jaws, said jaws being similar and being of isosceles triangu-

- lar form and connected at each end of the base by a resilient connection normally holding the jaws in approximately parallel relation and spaced apart from each other, a grip or handle, and a shank connecting one jaw to the grip or handle, said shank being secured to the outer face of one jaw and having a reduced portion engaging one end of the grip or handle.
- 18 2. A tool of the character specified, comprising a pair of gripping jaws, said jaws being similar and being of isosceles triangular form and connected at each end of the base by a connection normally holding the

jaws in approximately parallel relation and 15 spaced apart from each other, a grip or handle, and a shank connecting one jaw to the grip or handle.

3. A tool of the character specified, comprising a pair of triangular jaws, a connection between the jaws at each end of the base for normally holding the jaws in approximately parallel and spaced relation, and a handle connected with one of the jaws.

DAVID F. CURTIN.
